UNITED STATES PATENT OFFICE.

ANTHONY A. FETTE, OF CINCINNATI, OHIO.

LINKING MACHINE.

Application filed April 19, 1920. Serial No. 375,074.

To all whom it may concern:

Be it known that I, ANTHONY A. FETTE, a citizen of the United States, residing at Cincinnati, in the county of Hamilton and 5 State of Ohio, have invented certain new and useful Improvements in Linking Machines, of which the following is a specification.

My invention relates to leather manufacturers and link assembling; and the objects 10 of my improvement are to provide for more rapid assembly of leather or other flexible links of belts used as apparel or for other purposes, or of other articles of similar manufacture, to provide for such operation 15 on links of various sizes and designs by simple adjustments or alterations, and to facilitate the supply of the links to the machine, and in general minimize the attention required to be given to the link-assembling operations. Other objects will appear 20 in the course of the ensuing description.

I attain these objects by the apparatus illustrated, for example, in the accompanying 25 drawings, in which—

Figure 1 is a rear elevation of the machine, parts only of the supporting structure or bed being shown;

Fig. 2 is a vertical cross-section on a plane 30 corresponding to the line 2—2 of Fig. 1;

Fig. 3 is a horizontal cross-section on a plane corresponding to the line 3—3 of Fig. 1;

Fig. 4 is a detail side elevation of the jaw-opening mechanism;

Fig. 5 is a detail front elevation of the same;

Fig. 6 is an enlarged vertical longitudinal section of part of the machine, on a plane 40 corresponding to the line 6—6 of Fig. 2;

Fig. 7 is a further enlarged detail side elevation of the instrument for inserting a billet into the machine to begin making a belt;

Fig. 8 is a partial section corresponding to Fig. 6, showing a stage of operation more advanced than that shown in Fig. 6, the scale being that of Fig. 7;

Fig. 9 is a similar view showing a further stage of the operation;

Fig. 10 is a sectional plan view of these parts of the machine at the stage of operation shown in Fig. 9, the section being on a plane corresponding to the line 10—10 of that figure;

Figs. 11, 12 and 13 are views similar to

Figs. 8 and 9, showing still further stages of the operation;

Fig. 14 is a sectional plan view of a modified link-supply device, the section being on a plane corresponding to the line 14—14 of Fig. 1;

Fig. 15 is a vertical lengthwise section of the same, on a plane corresponding to the line 15—15 of Fig. 14;

Fig. 16 is a detail plan or pattern of the link for which the machine is shown as adjusted in all of the preceding illustrations;

Fig. 17 is a similar view of a length of belt or chain made from such links;

Figs. 18 and 19, 20 and 21, 22 and 23, and 24 and 25 are respectively in each instance, views similar to Figs. 16 and 17, of modified links for the assembly of which the machine is capable of adjustment, and of lengths of belts or chains made from the links; and

Fig. 26 is a detail plan view of a double gripper for operating upon the link of Figs. 24 and 25.

The machine comprises a bed-plate 1, which may have suitable legs 2, parts of which are shown in Fig. 1, or other means by which it may be suitably supported on a floor or a bench. This bed-plate 1 is of 85 comparatively long and narrow rectangular shape, and some distance to the left from its right-hand end it has on its bottom depending bearings 3 and 4, near the front edge and near the middle of the plate, respectively, in front-to-rear alinement. A shaft 5 is journaled in these bearings 3 and 4, with a projection forwardly of the front bearing having fixed thereon the handwheel 6 with a crank handle 7. This shaft 5 also 90 has a projection to the rear of the rear bearing, on which projection are fixed an eccentric 8, next to the rear bearing 4, a cam 9 to the rear of the eccentric 8, and, at the rear end of the shaft, a crank 10. A collar 95 5' fixed on the shaft 5 in front of the front bearing 3 acts together with the eccentric 8 against the rear bearing 4, to prevent undue end play of the shaft 5.

The bed-plate 1 has a wide lengthwise slot 105 11 near its right-hand end, and to the left, a narrower lengthwise slot 12, and between these, fixed in a suitable opening, is an upright post or standard 13, extending above and below the plate for considerable distances. The primary feeder comprises the magazine 14, a rectangular box-like element,

slidable along the slot 11, extending above and below the plate 1 and held down with ledges 15 bearing on the plate top, by cleats 16 against the plate bottom-surface. The 5 horizontal cross-section of the magazine interior is conformed to the pattern of the link to be operated upon; the links lying thereacross in a pile. A follower 17 of the same pattern extends across under the pile and 10 has stems 18 depending into casing-tubes 19 fixed in and depending from the magazine bottom and having caps 20 on their lower ends confining coil springs 21 against the follower bottom, around the respective 15 stems 18.

When slid to the left, the left end of the magazine 14 is against the standard 13; and this standard 13 has a vertical slot through it from right to left, from the top of the 20 standard down to shortly below the top edge of this magazine end. Below that, the standard 13 is slotted partly through its lower end, making it channelled, on its left-hand side.

25 An intermediate feeder 22, which will be described later, extends across the top of the magazine 14, covering the major right-hand part of its open top when the magazine is slid against the standard 13 as just described; this intermediate feeder 22 being fixed to the bed-plate 1 on opposite blocks 23 (Fig. 10). Sliding the magazine 14 to the right brings it out from under this intermediate feeder 22, for putting the links into 30 the magazine; and when slid thereunder, the intermediate feeder holds the links down in the magazine, as pressed up by the springs 21.

It is the purpose of the machine to successively withdraw the links off the pile in 40 the magazine in their initial posture, which, as here shown, is horizontal, through preceding links projected, directly from that initial posture of those preceding links, up 45 from the slot or throat of the standard 13, in the through slot of said standard; and to successively feed the links down through the throat after the preceding links have thus been drawn through or into them, the feeding-down operation causing doubling-up of 50 the link just drawn in, ready for the next succeeding link to be drawn through this doubled-up link. The machine thus comprises, broadly, two feeds at substantially 55 right-angles to each other, i. e., one, by a lengthwise feeder, from right to left, and the other, by a cross-feeding means, downward, as herein shown; and as shown also, the shaft 5 is adapted to drive the mechanisms 60 for effecting both feeds, as well as certain parts to coat and assist in the feeding operations.

The cross-feeding means, which, as here shown, is a down-feed mechanism, comprises 65 a feed-bar 24 with a corrugated face 25 in

the throat 26 formed by the aforescribed channel or slot in the standard 13. The corrugations 25 are formed by diagonal grooves at right angles, which I find do not mar the material. This feed-bar 24 has parallel up-right grooves 27 in its face, and has the middle part 28 of this face cut away at top and bottom, between the grooves 27. Another feed-bar 29 is like a small rectangular frame, with vertical side parts slidingly occupying the grooves 27, and top and bottom parts in the spaces left by the cutting away of the middle part 28 of the other feed-bar 24, and with the faces of these side and bottom parts corrugated and facing to the right along 75 with the corrugated face of the feed bar 24.

This second feed-bar 29 with its corrugated face in the throat 26 is yieldably held over to the right by small helical upper springs 30, interposed between its top part 80 and a bar 31, and similar springs 32 interposed between its bottom end part and small brackets 33 fixed to the side parts of the standard 13. Thus, when the throat 26 is otherwise empty, the corrugated face of this 85 feed-bar 29 will be against the bottom wall of the throat channel. The spring-retaining means in either example also loosely engage the top and bottom ends of the feed-bar 29 and prevent any material amount of up and 90 down motion of this bar.

The first feed-bar 24 is slidable up and down in the slot 12, up through which both feed-bars project, and has guides 34 on its left side. A presser-head 35 is slidable toward and from the throat 26 on guides 36 on the bed-plate bottom, has a rectangular opening 37 occupied by the cam 9, and has a socket 38 containing three small but stiff helical springs 39 compressed between its 100 inner end and a small upright bearing-bar 40 of I-beam cross-section (Fig. 3) with one side in the socket entrance and with its flanges behind flanges 41 extending in from the socket sides, and with the other side of 105 this bearing-bar 40 against a wedge 42 in an upright groove in the left side of this wedge 42, which wedge is held between the guides 34 and bears on the surface 43 of the feed-bar 24 between these guides 34, which surface 110 is inclined to the left from its top downward for a considerable distance. This wedge 42 is adjusted up and down by means of a screw-rod 44 swiveled to its bottom by a pin 45 and passing down through an eye 46 fixed on 115 the lower part of the feed-bar 24, with nuts 47 above and below the eye to fix the adjustment. The socket 38 has partitions 48 between and positioning the several springs 39, which latter afford a strong yet readily 120 yielding pressure, better than would a single spring of equal strength. A tension spring 49 (Fig. 1) is stretched from a pin 50 on the side of the feed-bar 24 at the rear, to a pin 51 on the rear side of the presser-head 35; 125 130

thus yieldably holding this head 35 and the feed-bar 24 and intervening parts together, allowing them to yield apart or come together under the control of the springs 39, 5 and allowing the feed bar to be thus controlled while sliding up and down relatively to the presser-head 35. This feed-bar 24 is guided in this up and down movement by the sides of the slot 12 in the bed-plate 1, 10 and by the sides of the throat 26.

This movement is effected by means of a lever 52 fulcrumed on the lower end part of a leg 53 depending from the bottom of the bed-plate 1 in front of the feed-bar; this 15 lever 52 being pivoted, at the right of its fulcrum, to the lower end part of the downward extension 54 of the feed-bar 24, and having at the left of its fulcrum a lengthwise slot 55 with a block guided therein as 20 adjusted along the lever 52 by a screw 56 in the end of the lever. This block makes up part of a pivotal connection to the lower end part of the eccentric rod 57, having a strap around the eccentric 8 on the shaft 5 as 25 before described. This rod 57 comprises a middle section 58 threaded into the terminal sections, for adjusting the length of the eccentric rod.

The cam 9 has its periphery made up of 30 two opposite sectors of unequal radius; the one of greater radius being about 120° in extent and the opposite one being about 180° in extent, and the two being joined by straight parts at their opposite ends. This 35 cam 9 and the eccentric 8 are so relatively positioned on the shaft 5 that the cam 9 will force the feed-bar 24 to the right as the lever 52, actuated by the eccentric 8, begins to pull the feed-bar 24 downward; the opening 37 of the presser-head 35 being properly proportioned to cause this coaction of the cam therewith as the sector of greater radius swings up to the right. When the shaft 5 is going into the opposite half of its revolution, with the eccentric 8 raising the feed-bar 24, the cam 9, with this sector acting against the left-hand side of the opening 37, acts, through the medium of the tension spring 49, to pull the feed-bar 24 and the 40 interposed parts to the left. This occurs while the eccentric 8 is beginning its raising action on the feed-bar. Thus, the movements of the feed-bar 24 to left or right are rather abrupt, as caused by the straight abrupt changes in radius of the cam 9, and occur during the slowest parts of the upward and downward movements of the feed-bar by the eccentric 8; affording an approximately four-way motion.

60 The lengthwise feeder comprises a guide-bed 59 on the top of the bed-plate 1, running along the bed-plate from the standard 13 a considerable distance to the left. The gripper comprises a gripper-bar 60 which slides lengthwise of the guide-bed 59. This slid-

ing is effected by the crank 10 of the shaft 5 through the medium of a pitman 61 pivoted to the crank wrist and to a rocker 62 pivoted in and depending from the bed-plate 1, a pair of links 63 pivoted on opposite sides 70 of this rocker 62 nearer to the middle of the machine (Fig. 9) and to opposite sides of the lower end part of a lever 64 fulcrumed in the left-hand end part of the bed-plate 1 and extending thereabove with a lengthwise 75 slot 65 guiding a block 66 as adjusted along the lever by a screw 67 in the upper end of the lever 64, and a connecting rod 68 pivoted to the block 66 and to the left-hand end part of the gripper-bar 60. This connecting rod 68 has a middle section 69 screwed into its terminal sections for adjusting the length of the rod.

At its right-hand end, the gripper-bar 60 has the upper gripper-jaw 70 fixed to it by 80 means of an arm 71 extending down to the left under the gripper-bar end. The lower gripper-jaw 72 has an arm 73 extending up to the left across the upper-jaw arm 71, with a pivot 74 through both arms 71 and 73; 90 these jaws 70 and 72 and their pivot 74 and adjacent parts of the arms 71 and 73 being preferably like ordinary well-known pliers, out of which they may, in fact, be made, by 95 properly cutting and bending the arms or handles of the pliers to form the arms 71 and 73, and suitably modifying the plier jaws, as will be described. The lower-jaw arm 73 curves up from the pivot parts, with an upright part fixed to the right-hand end 100 of the upper gripper-bar 75, which extends some distance to the left over the lower gripper-bar 60.

The jaw-opening mechanism comprises a pusher-bar 76 that extends down through a 105 slot in the bed-plate 1, and is offset therewith to avoid the down-feed presser-head 33, which latter has its top recessed therewith (Fig. 6); and a roller 77 journaled transversely in the forked lower end of this bar 110 76 (Figs. 4 and 5) bears on the periphery of a nose-cam 78 fixed on the shaft 5 between the down-feed cam 9 and the crank 10. The nose 79 of this cam 78 is substantially radial to the shaft 5 on its side where it leaves the 115 roller 77 (the shaft being rotated to the right of the operator at the front of the machine, as indicated by the arrow in Fig. 1), and the opposite side of the nose in a rather abrupt curve eccentric to the shaft, 120 to rapidly raise the pusher-bar 76 as the nose approaches under the roller 77. The middle of the bar 76, above the bed-plate 1, is slotted for the lower gripper-bar 60 to pass through it and permit the required up and down movement of the bar 76; and the upper end of this bar 76 is forked, straddling the upper gripper-bar 75, with a roller 80 journaled transversely in the fork members 125 under said bar 75. Also, this upper gripper- 130

bar 75 is recessed on its bottom, so that the roller 80 contacts with a surface that recedes upward from both ends toward the middle, in a gradual curve, which is rather more abrupt 5 at the left end. This pusher-bar 76 is guided in its up and down movement by guides 81 fixed upright along opposite sides thereof, on the bed-plate 1. The upper jaw 70 has a slight depending barb 82 near its tip, to enter a 10 slit or slot in the link and thus positively hold the link in addition to the gripping effect of the closed jaws. The lower jaw 72 is shorter than the upper jaw 70; its tip coming just behind the barb 82 when the 15 jaws close.

The link A used to exemplify the machine operation comprises a body *b* with two slots or slits *c* and *d* across its middle, near its right end and its left end, respectively, and 20 a tongue *e* joined to its left end by a narrower neck *f*; the tongue *e* having its free left end pointed, and the slit or slot *a* being across the middle of this tongue *e* near said end. The chain 83 is made up of these 25 links A by folding each link at its neck *f*, which, by proper location of the slits or slots *a*, *c* and *d*, causes the slits or slots *a* and *d* to register; and when this neck *f* occupies the registering slits or slots *a* and *d* 30 of the next preceding link in the belt or chain, the opposite end slit or slot *c* will be between and registering with these registering slits or slots *a* and *d*. With preceding links, thus joined, lying down along the 35 throat 26, the last-assembled link will be doubled up with these three slits or slots thus registering, in the path of the gripper, where the links are pulled down into the throat through the entrance at the adjacent 40 end of the guide-bed 59. Thus, as the gripper moves to the right as just before described, it passes through these three registering slits or slots *a*, *c* and *d* (Fig. 8) and on its return motion as described, it draws 45 the next link A through the slits or slots of said preceding link; the parts being so adjusted that the gripper is released from the link at the instant that the neck *f* is half-way through the slits or slots. It is 50 during the next right-hand stroke of the gripper, during its approach to the pulled-through link, that the down-feed mechanism, comprising the feed-bars 24 and 29 and their operating elements as before described, pulls the completed part of the chain or belt down just far enough to double this link up, due to pulling it into the throat 26, with its slits or slots *a* and *d* registering with the intervening slot *c* of the preceding 55 link, ready for the next pulling-through operation of the gripper or lengthwise feeder mechanism.

As these links are usually very flexible, it is preferable to have means for supporting 60 them when they are thus doubled up for the

gripper to pass through to the right, and also when the next succeeding link is being pulled through, to the left. But the supporting means at the left must be out of the way of the gripper when the latter is passing through to the right; and the right-hand supporting means must be out of the way of the right-hand part of the link when the link is to double up with the left-hand part, as must also the left-hand supporting 75 means be out of the way of this rising left-hand part.

I provide for this by making the left-hand support as a slide-bar 84 guided to slide up and down on the left side of the 80 standard 13, with a nose 85 on its lower end, inclined over toward the entrance to the throat 26 and having a middle recess in its tip for the passage of the gripper; the side parts 86 of the tip extending down to afford 85 ample bearing against the link A at opposite sides of its slit or slot *a* when doubled up as before described. A shaft 87 is journaled across the top part of the standard 13, and on this shaft, in the slot of the 90 standard, are fixed short arms 88, with links 89 connecting these arms 88 to the upper end of the slide-bar 84. To the rear of the standard 13, the shaft 87 projects out and has fixed on it an arm 90, projecting to the 95 left; and a connecting bar 91 has a slot 92 along it near its upper end, holding a wrist 93 fixed near the free end of the arm 90, the lower end part of this bar 91 being connected to the wrist of the crank 10 along 100 with the pitman 61 before described. The slot 92 is of such length and the other parts are so proportioned that the slide-bar 84 is slid down suddenly just as the gripper starts pulling the one link through the 105 other, and as suddenly pulled up during the opposite period of the gripper stroke, when the link must double up; the hand-wheel 6 being turned over to the left (or to the right of an operator at the front of the machine) to cause this coaction.

I prefer to provide the right-hand support as a lever 94 having a middle fulcrum 95 in the standard 13, to swing in the slot of the standard, and having its lower end 115 recessed at its middle to straddle the gripper and engage its side parts at opposite sides of the link slots or slits. It also preferably has a small slide-plate 96 across the middle recess guided in a suitable cavity 120 in the lever, and yieldably held down by a spring 97 compressed between its upper end and the upper end of the cavity, the latter being enlarged to receive the spring, with a shoulder 98 at the lower end of the enlargement, against which engages a lug 99 on the slide plate 96 to limit the downward movement of this plate. Thus, the slide-plate 96 can rise as the gripper passes thereunder, always keeping close to the upper 125 130

edge of the link slit or slot *d* as the gripper passes therethrough. The lower edge of this slit or slot is against the adjacent end of the throat 26. In this way, the link is supported practically entirely around its slit or slot *d* so as not to be distorted by the passage of the gripper therethrough. The upper end part of the lever 94 is pivoted to one end of a connecting member 100, the other end of which is pivoted to the upper end part of a post 101 fixed on the left end part of the gripper bar 60. This member 100 is made in two sections, screwed together, so that its length can be adjusted. These connections cause the gripper bar 60 to swing the lower end parts of the lever 94 down to the left as the gripper bar 60 advances, opposing these parts to the push of the gripper on the doubled-up link; and to swing these parts up to the right, out of the way, during recession of the gripper when the just pulled-through link must double up under the action of the downward or cross-feeding mechanism.

The construction of a belt is begun usually with a billet 102 (Fig. 1) having slits through which the first link A is drawn. To permit ready insertion of this billet, as well as withdrawal of the completed belt, or for any other purpose requiring release of the down-feed mechanism, a short handle-lever 103 is fulcrumed on one side of the lower end part of the standard 13 and lies across and is pivoted to the lower end part of the non-reciprocating feed-bar 29, so that pressure to the right on the outer end or handle 104 of this lever draws the lower end of this feed-bar 29 to the left, away from the chain or belt held by the feed-bar in the throat 26. The hand-wheel 6 is rotated so that the reciprocating feed-bar 24 is drawn away from the chain or belt; and these operations leave the chain or belt free to be readily withdrawn; or, at beginning, leave ample opening for insertion of the billet 102 up through the throat until the billet slots are above the upper end of the throat, ready to receive the first link A through the slots, according to the operation as has been described. To facilitate this insertion, I prefer to provide an implement 105 (Fig. 7) comprising a strip 106 long enough to reach the entire length of the throat 26, with a cross-piece 107 on its lower end part that engages with the lower end of the standard 13 and limits the upward extension of the strip to a point just below the path of travel of the cross-feed elements. On one face of this strip 107 is a gauge-piece 108, extending up from the cross-piece 107, with its upper end recessed to receive the lower end of the billet 102; the recess preferably being of approximately the same shape as the received billet end, and the extent of this gauge-piece 108 upward being such, in pro-

portion to the billet length, as to cause the billet slots to come in the aforesaid path when the implement is stopped as just described. This implement is made of stiff material, as wood or metal; thus supporting the flexible billet for pushing the latter endwise up through the throat 26. Various implements of this kind may be furnished for billets of various shapes or lengths.

The intermediate feeder 22 comprises a feed-block 109, slideable lengthwise of the machine, along the top of the magazine 14, on guides 110 fixed to the blocks 23 on the bed-plate 1 at the sides of the slot 11 as before mentioned, and extending in toward each other partly across the magazine (Fig. 10). Near its right-hand end, the block 109 has a finger 111 pivoted in it on a transverse pin and extending down through a slot in the block; and a short distance to the left, 85 is a similar finger 112, similarly mounted. These fingers 111 and 112 are adapted to extend their lower tips slightly below the block bottom when their longer upper parts are swung to the left; and these upper parts 90 have links 113 pivoted to them, so that they swing in unison. At the left end of the block 109, a third finger 114 is pivoted on a transverse pin near the block bottom, with the lower tip of the finger adapted to extend 95 below the block bottom when the upper longer part of the finger is swung to the left; this part being connected to the other fingers 111 and 112 by a link 115, which latter is flanked by upwardly extending brackets 116 100 on the block top. A small beam 117 is fulcrumed in the upper parts of these brackets 116, with its left end against the upper part of the finger 114, and held to incline down to the left by a small tension spring 118; 105 so that depression of its opposite or right end swings this finger 114, and with it the fingers 111 and 112, to extend their tips below the block bottom, as just described.

A long lever 119 is fulcrumed on the shaft 110 in the top part of the standard 13, and has its longer arm inclined down to the feed-block 109, with the lower end part of the arm slotted, so that side parts flank the feed-block brackets 116, with slots lengthwise of 115 the arm, receiving respective opposite trunnions 120 fixed in the adjacent sides of the upper parts of the brackets 116. Just above its end slot, this arm has a bearing-block 121 fixed on it, in which is fulcrumed a short 120 pusher-arm 122, depending therefrom and having a roller 123 journaled transversely in its lower forked end part, and held toward the arm or lever 119 by a small tension spring 124. These various parts are so 125 proportioned that when the lever or arm 119 swings down to the left it slides the feed-block 109 bodily along the magazine top toward the throat 26, by the engagement of the trunnions 120 in the arm slots; and 130

it also tilts the three fingers 111, 112 and 114 to extend their tips below the block bottom as before described, by the engagement of the roller 123 with the right end part of the beam 117. This actuation of the fingers ceases when the roller 123 rides down over the end of the beam 117, as permitted by the spring 124, when the upper part of the middle finger 112 has engaged a small stop-screw 125 threaded through the base of one of the brackets 116. Thus, the amount of the finger-tip extension may be adjusted, for links of different thickness that are fed to the left off the pile in the magazine 14 by the engagement of the tips in the slots or slits of the links; the tips of the fingers 111, 112 and 114 engaging, respectively, in the slits or slots *c*, *d* and *a*, and the flexible link being prevented from buckling up under the finger-tip pressure by the smooth bottom of the feed-block 109 sliding thereover. On return of this feed-block to the right, between feeds, the fingers are pushed back, withdrawing their tips, by a small spring 126 against the middle finger 112 around the stop-screw 125 and against the bracket 116.

A lip-plate 127 slides in a recess very close to the bottom of the feed-block 109, across the left end thereof, and is held to the left by a spring 128 compressed between the inner end of the plate and the opposite end of the recess, which latter is enlarged to hold the spring. The finger 114 has a recess in its end through which the plate 127 passes with shoulders 129 engaging with side parts of the finger 114 (Fig. 10) preventing its escape from its guiding recess. The plate 127 is thus extended across the part of the link A to the left of the feed-block, to prevent buckling-up of this part before the block slides thereover, when the gripping device of the lengthwise feeder is advancing onto this part of the initially fed link.

The mechanism just described has its parts so proportioned and adjusted that the pusher-bar 76 rises and elevates the upper gripper-bar 75 and swings the lower gripper-jaw 72 down away from the upper jaw 70 immediately after the pointed ends of the jaws have passed into the slits or slots of the link A, doubled up in the upper end of the throat 26 as before described; and thus continues to open the jaws until the barb 82 has passed into the nearest slit or slot *a* of the top link A in the magazine 14; this link being initially fed to the left at the end of the jaw advance, by the intermediate feeder before described, operated in the proper time by means of links 130 with their lower end parts pivoted to levers 131 fulcrumed near their left ends on links 132 pivoted to the sides of the guide-bed 59 and having a pivotal connection, shortly to the right of its fulcrum, with the upper end part of the pusher-bar 76; the upper end

part of the link 130 having a lengthwise slot receiving a pin 133 fixed in the shorter arm of the long initial-feed lever 119, extending to the left from the fulcruming shaft 87 in the standard 13. The proportions of these parts, and the length of the slot of the link 130 being such that this intermediate feeding is accomplished suddenly during this last stage of jaw advance, the opened jaws and the link approach each other. The lower jaw 72 is rather sharply tapered and shorter than the upper jaw, to come behind the barb 82 thereof. This lower jaw passes under the link while the upper jaw 70 passes over the link, until the barb 82 is over the slit or slot *a*. At this juncture the radial side of the cam nose 79 passes the roller 77, and the jaws are suddenly closed onto the link by the action of a tension spring 134 connected to the left end part of the upper gripper-bar 75 and to the lower gripper-bar 60 at one side. The degree to which the jaws close is limited by a stop-post 135 fixed in the lower bar 60 and engaged by the bottom of the upper bar 75; so that the jaws do not close too tightly on the link. The swinging of the feed-block 109 back to the right, after the link has thus been gripped, is effected by means of the connecting-bar 136, having its left end part pivoted to an upward extension of the post 101, and this bar 136 having a lengthwise slot near its right-hand end, receiving a pin 137 fixed in the upper free end part of an arm 138 fixed to the long lever 119; the length of this slot being such that the feed-block 109 is slid back during the last stage of the left-hand motion of the gripping device.

In this last stage, when the jaws have pulled the link A through to the right distance, as described for the first example, an engaging screw 139 screwed to the left through a lug 140 on the bottom of the upper gripper-bar 75 engages with a trip 141 hung between the members of a standard 142 that flank the guide-bed 59 and the gripper bars, this trip swinging on a transverse pin through the members, just under the upper bar 75, and rising under the pressure of the engagement, thus raising the upper gripper-bar 75, which opens the jaws and releases the link, ready to double up as drawn down into the throat 26 by the cross-feeding or down-feeding mechanism, as before described.

As the lower jaw 72 swings down as it passes through the doubled-up link A, a lower receding right-hand support is desirable, to prevent buckling of the link material just below its slots or slits. This is provided by continuing the recess of the standard 12 some distance below the top of the magazine 14, and mounting therein a small bar 143 pressed up by springs 144, and having its upward motion limited by side pins 145 130

in slots in the recess sides (Figs. 8 to 13), yielding downwardly under the pressure of the downwardly opening lower jaw 72 and rising again as the jaw closes. The guide-bed 59 is terminated some distance to the left of the standard 13, with the jaws and jaw arms overhanging it, so that the latter are free to swing; and the lower left-hand support for the link A when upturned in the throat 26 is afforded by the bar 31, previously mentioned, which has its top suitably recessed to permit the passage and swinging of the lower gripper-jaw 72.

In the modification of Figs. 14 and 15, the primary feeder comprises, instead of the single sliding magazine 14, four such magazines 14', substantially the same as the one of the other example, but set in a turret-plate 161, at equal intervals therearound; the plate 161 turning in a circular opening in the modified bed-plate 1'', with an upper annular shoulder 162 down on the bed-plate top and with cleats 163 up against the bed-plate bottom. The periphery of the turret-plate 161 has four notches 164 at equal intervals therearound; and a dog 165, sliding in lugs 166 on the bed-plate top at one corner, enters any one of these notches under the pressure of a spring 167. The guides 110' for the feed-block 109 are on the standard 13', overhanging the turret-plate 161, and the notches 164 are so related to the magazines 14' that at each stop one of the magazines is registered under the feed-block 109, for feeding the links therefrom. Thus, exposed magazines 14' can be filled while the machine is taking links from the registered magazine. A retaining element 168 is fork-shaped, with its prongs to go through openings 169 in the sides of the magazine 14' across the top of the pile of links therein, to prevent these from rising out of the magazine as pressed up by the follower 17; such an element being thus inserted in each magazine as it is filled, to be withdrawn when the magazine has passed under the feed-block 109, after which this retains the links, as before described.

Any of the links B, C or D of Figs. 18, 50 20 and 22, respectively, may be assembled by properly adjusting the operating parts of the machine, as will be described. The link E of Figs. 24 and 25, with two tongues h, each having a separate slit or slot a', requires a changing of the gripper device. This is provided for by making the jaw arms 71 and 73 readily detachable from the gripper-bars 60 and 75, as by being screwed thereto as shown. This allows the arms 133' 55 and 135' of the double jaws 132' and 134' (Fig. 26) to be similarly attached to the bars 60 and 75, respectively. Thus, the separate jaws 132' and 134' grip the respective tongues h with their separate bars 144' in 60 the respective slits or slots a'.

It will be seen that although the number of slots or slits in the various links of Figs. 16 to 25, inclusive, varies, from four in Figs. 20 and 21 to only two in Figs. 22 and 23, or only two transversely aligned pairs in 70 the double-tongued link of Figs. 24 and 25, the factors governing their assembly by the machine are the distances of the adjacent slits or slots from the neck of the link. Of course the additional slits or slots, if any, 75 must register with the proper slit or slot of these two; but this is a matter of link design. If the lengthwise feeder barb engages in the first left-hand slit or slot, as a of Fig. 16, a' of Fig. 24, or a'', c' or c' of Figs. 18, 20 or 80 22, respectively, and travels far enough to the left to stop the neck f of Fig. 16, necks f' of Fig. 24, or the neck f'', f' or f' of the other three, over the throat 26, and the cross-feeding or down-feeding means draws down 85 far enough to bring the next registering slits or slots a and c of Fig. 16, a' and c' of Fig. 24, or a'' and d'', c' and c' and d' and d', respectively, of Fig. 20, or b' and b' of Fig. 22, in the path of the lengthwise 90 feeder gripper at the next stroke thereof, then the assembly will be accomplished by the machine. It will further be seen that many other designs of links may be used, 95 providing these conditions are met.

The cross-feeding or down-feeding adjustment is made by setting the connection of the lever 52 and eccentric rod 57 toward or away from the lever fulcrum, by means of the screw 56; and the feed-bar 24 is caused 100 to stop its upward stroke always at about the same height with any length of stroke, by lengthening or shortening the eccentric rod 57 by means of its middle section 58.

The lengthwise feeder adjustment is made 105 by similarly setting the connection of the lever 64 and gripper-bar connecting rod 68 toward or away from the lever fulcrum, and properly lengthening or shortening the connecting rod 68 by means of the middle section 69.

The jaw opening at the left end of the gripper stroke is made earlier or later by adjusting the trip-engaging screw 139 to the left or right. The right-hand closure of the gripper needs no adjustment in this respect; the magazine, corresponding to the magazine 14 or 14', being properly designed to hold the particular different link so that the latter is properly intermediately fed to the 120 gripper, which is stopped always at about the same point at the right end of the stroke, by virtue of the adjustment of the connecting rod 68 as before mentioned. The magazines are readily removable, and the magazine 14 or plurality of magazines 14', with 125 interior conforming to the particular link design, may be substituted; the link-containing hollow interior of the magazine being the proper distance from the left end 130

of the magazine that comes adjacent to the standard 13.

Links of different thicknesses are accommodated by making the projection of the 5 intermediately feeding fingers 111, 112 and 114 less or greater by means of the stop-screw 125, and making the jaw closure more or less complete by means of the adjustable stop-post 135, and by lowering or raising 10 the wedge 42 to cause the cross-feeding or down feeding bar 24 to vary the amount of its approach to the right.

The right-hand supporting lever 94 is properly adjusted by means of the screwed-on right-hand terminal part of the connecting member 100.

Variation of thickness of links of the same lot is prevented from resulting in damage to the machine or to the links by means of the 20 plurality of small but stiff springs 39 between the wedge 42 and presser head 35.

Operation.—The proper adjustments for any particular link having been made as just described, a supply of links sufficient to 25 make one belt are placed in the magazine 14, or in each magazine 14', and brought to the left therein, close to the standard 13. A billet 102 is inserted by means of the implement 105 until its slit or slot is in the 30 path of the lengthwise feeder gripper; the cross-feeding or down-feeding means being opened by means of the lever 103, with the hand-wheel 6 rotated to a point at which the gripper is withdrawn away from the throat 35 26 and whereby the cross-feeding or down-feeding bar 24 is withdrawn from the throat wall, permitting free sliding of the billet up through the throat.

Upon turning the hand-wheel 6 to the 40 right of the operator at the front of the machine, the lengthwise feeder element is projected to the right (rear view) through the billet; after which the linking process will proceed incident to the coaction of the 45 machine parts as long as there are links in the magazine and as long as the hand-wheel is turned. Succeeding links are fed up by the follower 17 as fast as the top links are withdrawn.

50 The implement 105, inserted with the billet to begin the operation, is fed down along with the coextensive part of the belt, and drops out upon reaching the lower end of the throat, 26; it being understood that 55 the springs 39 permit this extra thickness to be fed along with the belt by the down-feed mechanism, as described, after which the remainder of the belt is fed in that way.

The crank 10 advances the gripper jaws, 60 in closed condition, through the billet or link slit or slot, to the right, during the upper half of the crank swing; and the nose 79 of the cam 78, through the pusher-bar 76 acting against the recessed lower side 65 of the lower-jaw upper gripper-bar 75,

swings the lower jaw 72 downward (Fig. 14), while the intermediate feeder, actuated through the bar 130 engaging the lower end of its slot with the pin 133 just at the end of the right-hand gripper travel, quickly 70 advances the top link from the magazine within reach of the open jaws. The lip-plate 127 is engaged by the upper jaw 70 and pushed back into the feed-block 109 as the jaw and block approach; thus preventing 75 the link from buckling upward and insuring that it is inserted between the jaws. The approach stops as the barb 82 of the upper jaw enters the slit or slot *a* (Fig. 15.) At about the same instant, the cam nose 80 79 passes from under the pusher-bar 76, and the spring 134 suddenly closes the jaws; while the crank 10 is just going into its lower half-circle and beginning to pull the jaws to the left.

85 During the right-hand travel of the jaws, the right-hand supports, 94 above and 143 below, coact with the lengthwise feeder gripper; the plate 96 and the bar 143 following the inclines of the upper and lower 90 jaws, respectively. Also, on the return stroke, the left-hand support 84 is slid down.

Near the end of the right-hand travel of the lengthwise feeder grippers, the trip 141, 95 engaged by the screw 139, raises the upper gripper-bar 75, lowering the lower jaw 72, so that the link may pass down and disengage from the barb 82 under the action of the down-feed mechanism, which has now 100 begun to operate; the cam 9, swinging up to the right, pushing feed-bar 24 against the billet or links so far assembled, which were held up by feed-bar 29 (Fig. 1,) while eccentric 8 is passing its lowest point. This 105 downward motion of the left end of the link will be only slight and momentary (Fig. 11,) after which the continued operation of the down-feeding or cross-feeding means, during continued travel of the lengthwise 110 feeder grippers away from the link, will fold the link upward, as permitted by the right and left hand supports receding therefrom (Fig. 12,) and a completion of the downward or cross feed, as the eccentric 115 8 passes its highest point, will result in the parts of the link being brought together in upright position with their apertures or slits or slots registering and the gripper again approaching to pass through these 120 apertures (Fig. 13). Quick return of the feed-block 109 is caused by the bar 136 engaging the right-hand end of its slot with the pin 137 in the arm 138 of the lever 119.

The operation of the double grippers 125 (Fig. 26) will be understood to be practically the same, drawing the two distinct tongues *b* of a link *E* (Fig. 24) through respective distinct slits or slots or apertures *a'* of the preceding link, folded up as was de- 130

scribed for the other links. Likewise with any similar link of different design or dimensions; the machine being adjusted accordingly, as before described.

5 Where only a single magazine 14 is used, it is necessary to delay operation of the machine to refill the magazine for the next belt; but with the turret combination of Figs. 14 and 15 three magazines may be 10 filled while the machine is receiving from the fourth. Thus the machine may run continuously, and a single operator may attend several machines; the only attention to the supply being that of shifting the next 15 filled magazine 14' under the intermediate feeding device 22, and filling the emptied magazines as opportunity affords at some time before all become exhausted.

Also, the belt or chain may be made of 20 any required length by briefly stopping the machine and shifting in a newly filled magazine before the current one is exhausted. Or, as will be understood, the capacity of 25 a magazine may be increased by increasing its depth, for which there is ample space below the right-hand end of the machine. Such belt or chain of great length may thus be supplied as stock material from which any desired length may be cut, for use as 30 cords, braids, or for any purpose where a flexible chain-like or ornamental fabric may be desirable.

The apertures or slits or slots of the apertured link elements are illustrated as open 35 slots made by removing a part of the material of substantial width to form each one; but these may be formed by merely cutting the material along a single line for the required distance, forming what may be 40 more properly termed a slit, and the mechanism will engage its hook or barb, in either example, in such a slit and function as has been described. Also, it is found in practice that the lengthwise feeder element will penetrate an unslotted or unslootted link element 45 disposed across its path, and the barb 82, with the cooperation of the lower gripper jaw, will make effectual tractive engagement with the succeeding link element to 50 pull it through the aperture formed by the penetrating lengthwise feeder element. Such an operation, with link elements not having apertures previously formed; of course produces less presentable belts or 55 chains where no special provision is made for insuring cleanliness of cut of the penetrating element; but is useful for some purposes.

The machine is disclosed as hand-operated, but it will be obvious that a suitable operative connection for power operation may be added, or substituted for the hand-operating means.

Numerous other modifications are possible, within the scope of my invention, to

meet different conditions or requirements, and therefore, while certain constructional details are deemed preferable in connection with my invention, and I have shown and described these rather specifically in elucidating the construction and use of my invention, as is required, I do not wish to be understood as being limited to such precise showing and description, but having thus fully described my invention,

What I claim as new and desire to secure by Letters Patent is:

1. In a machine of the character described, a single primary feeder for successively feeding link elements into a path in an initial posture, a lengthwise feeder having an action successively advancing said link elements along said path and maintaining said initial posture of the link elements, cross-feeding means having an action disposing each thus advanced link element directly from said initial posture into a posture to extend across said path during the advance of the next link element along said path from said single primary feeder, and mechanism coordinating said actions of said lengthwise feeder and said cross-feeding means.

2. In a machine of the character described, a single primary feeder for successively feeding link elements into a path in an initial posture, a lengthwise feeder having an action successively advancing said link elements along said path and maintaining said initial posture of the link elements, an intermediate feeder having an action successively initially advancing said link elements along said path from said primary feeder to said lengthwise feeder, cross-feeding means having an action disposing each thus advanced link element directly from said initial posture into a posture to extend across said path during the advance of the next link element along said path from said single primary feeder, and mechanism coordinating said actions of said intermediate and lengthwise feeders and said cross-feeding means.

3. In a machine of the character described, a primary feeder for successively feeding link elements into a path, a lengthwise feeder having an action successively advancing said link elements along said path, an intermediate feeder having an action successively initially advancing said link elements along said path from said primary feeder to said lengthwise feeder, cross-feeding means having an action disposing each thus advanced link element into a posture to extend across said path during the advance of the next link element along said path, and mechanism coordinating said actions of said intermediate and lengthwise feeders and said cross-feeding means.

4. In a machine of the character de-

5. In a machine of the character described, a primary feeder for successively feeding link elements into a path, a lengthwise feeder having an action successively advancing said link elements along said path, cross-feeding means having an action disposing each thus advanced link element into a posture to extend across said path during the advance of the next link element along said path, mechanism coordinating said actions of said lengthwise feeder and said cross-feeding means, and means for disposing a first element across said path to be assembled with said link elements.
6. In a machine of the character described, a primary feeder for successively feeding link elements into a path, a lengthwise feeder having an action successively advancing said link elements along said path, cross-feeding means having an action disposing each thus advanced link element into a posture to extend across said path during the advance of the next link element along said path, means additional to said cross-feeding means for temporarily supporting the thus disposed link element during said advance, and mechanism coordinating said actions of said lengthwise feeder and said cross-feeding means.
7. In a machine of the character described, a primary feeder for successively advancing link elements into a path, a lengthwise feeder having an action successively advancing said link elements along said path, cross-feeding means having an action disposing each thus advanced link element into a posture to extend across said path during the advance of the next link element along said path, mechanism coordinating said actions of said lengthwise feeder and said cross-feeding means, and means for disposing a first element across said path, through said cross-feeding means, to be assembled with said link elements.
8. In a machine of the character described, a primary feeder for successively advancing link elements into a path, a lengthwise feeder having an action successively advancing said link elements along said path, cross-feeding means having an action disposing each thus advanced link element into a

posture to extend across said path during the advance of the next link element along said path, mechanism coordinating said actions of said lengthwise feeder and said cross-feeding means, means for varying the range of action of said lengthwise feeder, and means for varying the range of action of said cross-feeding means.

9. In a machine of the character described, cross-feeding means having an action successively disposing preceding link elements at a substantial angle to respective next succeeding elements, a lengthwise feeder having an action to penetrate said preceding elements and to return therethrough with said succeeding elements, and mechanism coordinating said actions of said cross-feeding means and said lengthwise feeder.

10. In a machine of the character described, cross-feeding means having an action successively folding preceding link elements into position at a substantial angle to respective next succeeding elements, a lengthwise feeder having an action to penetrate the folds of said preceding elements and to return through said folds with said succeeding elements, and mechanism coordinating said actions of said cross-feeding means and said lengthwise feeder.

11. In a machine of the character described, in which link elements are successively supplied from a single source in an initial posture, cross-feeding means having an action successively disposing preceding link elements directly from said posture into a posture to extend at a substantial angle to respective next succeeding link elements, a lengthwise feeder having an action to penetrate said preceding elements and return therethrough with said succeeding elements, and mechanism coordinating said actions of said cross-feeding means and said lengthwise feeder.

12. In a machine of the character described, in which link elements are successively supplied from a single source in an initial posture, cross-feeding means having an action successively folding preceding link elements directly from said initial posture into a posture to extend at a substantial angle to respective next succeeding link elements, a lengthwise feeder having an action to penetrate the folds of said preceding elements and return through said folds with said succeeding elements, and mechanism coordinating said actions of said cross-feeding means and said lengthwise feeder.

13. In a machine of the character described, in which link elements are successively supplied from a single source in an initial posture, cross-feeding means having an action successively disposing preceding link elements directly from said initial posture into a posture to extend at a substantial angle to respective next succeeding link ele-

- ments, a lengthwise feeder comprising a projection and having an action to penetrate said preceding elements and to engage said projection with said succeeding elements and to return through said preceding elements with said succeeding elements, and mechanism coordinating said actions of said cross-feeding means and said lengthwise feeder.
14. In a machine of the character described, in which link elements are successively supplied from a single source in an initial posture, cross-feeding means having an action successively disposing preceding link elements directly from said initial posture into a posture to extend at a substantial angle to respective next succeeding link elements, a lengthwise feeder comprising a gripper and having an action to penetrate said preceding elements and to grip said succeeding elements and to return through said preceding elements with said succeeding elements, and mechanism coordinating said actions of said cross-feeding means and said lengthwise feeder.
15. In a machine of the character described, in which link elements are successively supplied from a single source in an initial posture, cross-feeding means having an action successively disposing preceding link elements directly from said initial posture into a posture to extend at a substantial angle to respective next succeeding link elements, a lengthwise feeder comprising a gripper with a projection and having an action to penetrate said preceding elements and to grip said succeeding elements and engage said projection with said succeeding elements and to return through said preceding elements with said succeeding elements, and mechanism coordinating said actions of said cross-feeding means and said lengthwise feeder.
16. In a machine of the character described, cross-feeding means having an action successively disposing preceding link elements at a substantial angle to respective next succeeding link elements, a lengthwise feeder comprising a projection and having an action to penetrate said preceding elements and to engage said projection with said succeeding elements and to return through said preceding elements with said succeeding elements, and mechanism coordinating said actions of said cross-feeding means and said lengthwise feeder.
17. In a machine of the character described, cross-feeding means having an action successively disposing preceding link elements at a substantial angle to respective next succeeding link elements, a lengthwise feeder having an action to penetrate said preceding elements and to return therethrough with said succeeding elements, mechanism coordinating said actions of said cross-feeding means and said lengthwise feeder, and means for varying the relative ranges of action of said cross-feeding means and said lengthwise feeder.
18. In a machine of the character described, a structure having a throat, gripping means having a feeding action along a path across said throat, gripping means having a feeding action along said throat away from said path, and means to impart the respective feeding actions.
19. In a machine of the character described, a structure having a throat, a guideway on said structure at a substantial angle to said throat, tractive means guided in said guideway across said throat, means for reciprocating said tractive means across said throat, means having a feeding action along said throat away from said guideway, and means for imparting this feeding action.
20. In a machine of the character described, a structure having a throat, means having a feeding action along a path across said throat, means having a feeding action along said throat away from said path, means to impart the respective feeding actions, and a magazine feeding upward into said path near the place of meeting of said path and said throat.
21. In a machine of the character described, a structure having a throat, means having a feeding action along a path across said throat, means having a feeding action along said throat away from said path, means to impart the respective feeding actions, a magazine feeding into said path near the place of meeting of said path and said throat, and a self-adjusting follower in said magazine, acting at a substantial angle to said path.
22. In a machine of the character described, a structure having a throat, means having a feeding action along a path across said throat, means having a feeding action along said throat away from said path, means to impart the respective feeding actions, supporting means for the material operated upon by the machine, to approach and recede from the place of meeting of said path and said throat in sequence to said feeding actions, and mechanism to cause the approach and recession of said supporting means as aforesaid.
23. In a machine of the character described, a structure having a throat, a lengthwise feeder having a feeding action along a path across said throat, means having a feeding action along said throat away from said path, means to impart the respective feeding actions, supporting means for the material operated upon by the machine, to approach and recede from the place of meeting of said path and said throat in synchronism with the feeding actions and means operatively connecting said lengthwise feeder to said sup-

porting means to cause the approach and recession of said supporting means as aforesaid.

24. In a machine of the character described, a structure having a throat, means having a feeding action along a path across said throat, means having a feeding action along said throat away from said path, means to impart the respective feeding actions, a plurality of supporting means for the material operated upon by the machine, distinct from each other, to approach and recede from the place of meeting of said path and said throat at different stages of said feeding action along said path, and mechanism to cause the approach and recession of the respective supporting means as aforesaid.

25. In a machine of the character described, a structure having a throat, a lengthwise feeder having a feeding action along a path across said throat, means having a feeding action along said throat away from said path, a shaft, operative connections from said shaft to the respective means, whereby said shaft imparts the respective feeding action, a plurality of supporting means for the material operated upon by the machine, distinct from each other, to approach and recede from the place of meeting of said path and said throat at different stages of the feeding actions, an operative connection from said shaft to one of said supporting means, and an operative connection from said lengthwise feeder to the other one of said supporting means, to cause the approach and recession of the respective supporting means as aforesaid.

26. In a machine of the character described, a structure having a throat, a lengthwise feeder having a feeding action along a path across said throat, cross-feeding means having a feeding action along said throat away from said path, a shaft, means operatively connecting said shaft and said cross feeding means, to impart the cross-feeding action, a crank on said shaft, means operatively connected to said crank and to said lengthwise feeder, whereby said crank imparts said feeding action along said path, a plurality of supporting means for the material operated upon by the machine, distinct from each other, to approach and recede from the place of meeting of said path and said throat at different stages of the feeding actions, an operative connection from said crank to one of said supporting means, and an operative connection from said lengthwise feeder to the other one of said supporting means, to cause the approach and recession of the respective supporting means as aforesaid.

27. In a machine of the character described, a structure having a throat, a

lengthwise feeder having a feeding action along a path across said throat, means having a feeding action along said throat away from said path, means to impart the respective feeding actions, and supporting means for the material operated upon by the machine, yieldably engaging said lengthwise feeder near the place of meeting of said path and said throat.

28. In a machine of the character described, a structure having a throat, a lengthwise feeder having a feeding action along a path across said throat, means having a feeding action along said throat away from said path, means to impart the respective feeding actions, supporting means for the material operated upon by the machine, to approach and recede from the place of meeting of said path and said throat in sequence to said feeding actions, and mechanism to cause the approach and recession of said supporting means as aforesaid, said supporting means yieldably engaging said lengthwise feeder near said place of meeting of said path and said throat.

29. In a machine of the character described, a structure having a throat, means having a feeding action along a path across said throat, means having a feeding action along said throat away from said path, means to impart the respective feeding actions, and a magazine to supply material to said path mounted to move toward or away from the place of meeting of said path and said throat.

30. In a machine of the character described, a structure having a throat, means having a feeding action along a path across said throat, means having a feeding action along said throat away from said path, means to impart the respective feeding actions, a magazine to supply material to said path near the place of meet of said path and said throat, a follower in said magazine, acting at a substantial angle to said path, and means over said magazine opposed to the action of said follower.

31. In a machine of the character described, a structure having a throat, means having a feeding action along a path across said throat, means having a feeding action along said throat away from said path, means to impart the respective feeding actions, a magazine to supply material to said path near the place of meeting of said path and said throat, a follower in said magazine, acting at a substantial angle to said path, means over said magazine opposed to the action of said follower, and means whereby said magazine is movable away from this opposing means and away from said place of meeting of said path and said throat.

32. In a machine of the character de-

scribed, a structure having a throat, a lengthwise feeder having a feeding action along a path across said throat, means to impart said feeding action, a feed-bar in said throat, and 5 means to reciprocate said feed-bar along said throat in sequence to said lengthwise feeder action.

33. In a machine of the character described, a structure having a throat, a lengthwise feeder having a feeding action along a path across said throat, a shaft, an operative connection from said shaft to said lengthwise feeder, an eccentric and a cam on said shaft, a feed-bar in said throat, an operative 10 connection from said eccentric to said feed-bar whereby said eccentric reciprocates said feed-bar along said throat, and an operative connection from said cam to said feed-bar whereby said cam reciprocates said feed-bar 15 across said throat.

34. In a machine of the character described, a structure having a throat, a lengthwise feeder having a feeding action along a path across said throat, means to impart 20 said lengthwise feeder action, a feed-bar in said throat, means to reciprocate said feed-bar along said throat in sequence to said lengthwise feeder action, and means to reciprocate said feed-bar across said throat 25 near the respective ends of the reciprocation along the throat.

35. In a machine of the character described, a structure having a throat, a lengthwise feeder having a feeding action along 30 a path across said throat, means to impart said lengthwise feeder action, a feed-bar in said throat, means to reciprocate said feed-bar along said throat in sequence to said lengthwise feeder action, and a second feed- 35 bar yieldably pressed across said throat but prevented from material movement along said throat.

36. In a machine of the character described, a structure having a throat, a lengthwise feeder having a feeding action along 40 a path across said throat, means to impart said lengthwise feeder action, a feed-bar in said throat, means to reciprocate said feed-bar along said throat in sequence to said lengthwise feeder action, and means yieldably 45 connected to said feed-bar to reciprocate said feed-bar across said throat near the respective ends of the reciprocation along the throat.

37. In a machine of the character described, a structure having a throat, a lengthwise feeder having a feeding action along a path across said throat, means to impart said lengthwise feeder action, a feed-bar in said 50 throat, means to reciprocate said feed-bar along said throat in sequence to said lengthwise feeder action, and means comprising a cushion element, connected to said feed-bar to reciprocate said feed-bar across said

throat near respective ends of the reciprocation along the throat.

38. In a machine of the character described, a structure having a throat, a lengthwise feeder having a feeding action along a path across said throat, means to impart 70 said lengthwise feeder action, a feed-bar in said throat, means to reciprocate said feed-bar along said throat in sequence to said lengthwise feeder action, and means comprising a cushion element, yieldably connected to said feed-bar to reciprocate said feed-bar across said throat near respective ends of the reciprocation along the throat.

39. In a machine of the character described, a structure having a throat, a shaft, 80 an eccentric and a cam on said shaft, a feed-bar in said throat, an operative connection from said eccentric to said feed-bar whereby said eccentric reciprocates said feed-bar along said throat, and an operative connection 85 from said cam to said feed-bar whereby said cam reciprocates said feed-bar across said throat.

40. In a machine of the character described, a structure having a throat, a shaft, 90 an eccentric and a cam on said shaft, a feed-bar in said throat, an operative connection from said eccentric to said feed-bar whereby said eccentric reciprocates said feed-bar along said throat, and an operative connection 95 to said cam yieldably connected to said feed-bar whereby said cam reciprocates said feed-bar across said throat.

41. In a machine of the character described, a structure having a throat, a shaft, 100 an eccentric and a cam on said shaft, a feed-bar in said throat, an operative connection from said eccentric to said feed-bar whereby said eccentric reciprocates said feed-bar along said throat, and an operative connection 105 to said cam comprising a cushion element, connected to said feed-bar whereby said cam reciprocates said feed-bar across said throat.

42. In a machine of the character described, a structure having a throat, a shaft, 110 an eccentric and a cam on said shaft, a feed-bar in said throat, an operative connection from said eccentric to said feed-bar whereby said eccentric reciprocates said feed-bar 115 along said throat, and an operative connection to said cam comprising a cushion element, yieldably connected to said feed-bar whereby said cam reciprocates said feed-bar across said throat.

43. In a machine of the character described, a structure having a throat, a shaft, an eccentric and a cam on said shaft, a feed-bar in said throat, an operative connection from said eccentric to said feed-bar where- 120 by said eccentric reciprocates said feed-bar along said throat, an operative connection 125 from said cam to said feed-bar whereby said

- cam reciprocates said feed-bar across said throat, and a second feed-bar yieldably pressed across said throat but prevented from material movement along said throat.
44. In a machine of the character described, a structure having a throat, cross-feeding means having a cross-feeding action along a path across said throat, means to impart said cross-feeding action, a feed-bar in said throat, means to reciprocate said feed-bar along said throat in sequence to said cross-feeding action, and means to reciprocate said feed-bar across said throat near the respective ends of the reciprocation along the throat, comprising a presser-head, means to reciprocate said presser head, a wedge interposed between said presser-head and said feed-bar, and a connection between said presser-head and said feed-bar permitting them to be wedged apart.
45. In a machine of the character described, a structure having a throat, cross-feeding means having a cross-feeding action along a path across said throat, means to impart said cross-feeding action, a feed-bar in said throat, means to reciprocate said feed-bar along said throat in sequence to said cross-feeding action, and means to reciprocate said feed-bar across said throat near respective ends of the reciprocation along the throat, comprising a presser-head, means to reciprocate said presser-head, a wedge interposed between said presser-head and said feed-bar and a yieldable connection between said presser-head and said feed-bar.
46. In a machine of the character described, a structure having a throat, cross-feeding means having a cross-feeding action along a path across said throat, means to impart said cross-feeding action, a feed-bar in said throat, means to reciprocate said feed-bar along said throat in sequence to said cross-feeding action, and means to reciprocate said feed-bar across said throat near respective ends of the reciprocation along the throat, comprising a presser-head, means to reciprocate said presser-head, a wedge interposed between said presser-head and said feed-bar, a cushion element interposed between said presser-head and said wedge, and a yieldable connection between said presser-head and said feed-bar.
47. In a machine of the character described, a structure having a throat, a shaft, an eccentric and a cam on said shaft, a feed-bar in said throat, an operative connection from said eccentric to said feed-bar whereby said eccentric reciprocates said feed-bar along said throat, and an operative connection from said cam to said feed-bar whereby said cam reciprocates said feed-bar across said throat, comprising a presser-head, means to reciprocate said presser-head, a wedge interposed between said presser-head
- and said feed-bar, and a connection between said presser-head and said feed-bar permitting them to be wedged apart.
48. In a machine of the character described, a structure having a throat, a shaft, an eccentric and a cam on said shaft, a feed-bar in said throat, an operative connection from said eccentric to said feed-bar whereby said eccentric reciprocates said feed-bar along said throat, and an operative connection from said cam to said feed-bar whereby said cam reciprocates said feed-bar across said throat, comprising a presser - head, means to reciprocate said presser-head, a wedge interposed between said presser-head and said feed-bar, and a yieldable connection between said presser-head and said feed-bar.
49. In a machine of the character described, a structure having a throat, a shaft, an eccentric and a cam on said shaft, a feed-bar in said throat, an operative connection from said eccentric to said feed-bar whereby said eccentric reciprocates said feed - bar along said throat, and an operative connection from said cam to said feed-bar whereby said cam reciprocates said feed-bar across said throat, comprising a presser - head, means to reciprocate said presser-head, a wedge interposed between said presser-head and said feed-bar, a cushion element interposed between said presser-head and said wedge, and a yieldable connection between said presser-head and said feed-bar.
50. In a machine of the character described, a structure having a throat, a guideway on said structure at a substantial angle to said throat, tractive means guided in said guideway across said throat, a shaft, a lever connected to said tractive means, a member connected to said shaft for reciprocation thereby and having a connection to said lever adjustable along said lever, for variably reciprocating said tractive means across said throat, means having a feeding action along said throat away from said guideway, and means for imparting this feeding action.
51. In a machine of the character described, a structure having a throat, cross-feeding means having a cross-feeding action along a path across said throat, means for imparting this cross-feeding action, a feed-bar in said throat, a shaft, a lever connected to said feed-bar, and a member connected to said shaft for reciprocation thereby and having a connection to said lever adjustable along said lever, for variably reciprocating said feed-bar along said throat.
52. In a machine of the character described, a structure having a throat, a guideway on said structure at a substantial angle to said throat, tractive means guided in said guideway across said throat, a shaft, a lever connected to said tractive means, a member connected to said shaft for reciprocation

thereby and having a connection to said lever adjustable along said lever, for variably reciprocating said tractive means across said throat, a feed-bar in said throat, a lever 5 connected to said feed-bar, and a member connected to said shaft for reciprocation thereby and having a connection to said lever adjustable along said lever, for variably reciprocating said feed-bar along said 10 throat.

53. In a machine of the character described, a feeding member, a shaft, a lever connected to said feeding member, and a member connected to said shaft for reciprocation thereby and having a connection to 15 said lever adjustable along said lever for variably reciprocating said feeding member.

54. In a machine of the character described, feeding members, a shaft, levers connected to the respective feeding members, and members connected to said shaft for reciprocation thereby and having connections to the respective levers adjustable 25 along the respective levers, for variably reciprocating the respective feeding members.

55. In a machine of the character described, a structure having a throat, a lengthwise feeder having a feeding action 30 along a path across said throat, means having a feeding action along said throat away from said path, means to impart the respective feeding actions, auxiliary means near said path, to operate upon material fed 35 along said paths, and an operative connection from said lengthwise feeder to said auxiliary means comprising a slotted bar and a pin in the slot, whereby said auxiliary means is completely actuated during a part 40 of the actuation of said lengthwise feeder.

56. In a machine of the character described, a structure having a throat, a lengthwise feeder having a feeding action along a path across said throat, means having a feeding action along said throat away from said path, a shaft, means operatively connecting said shaft and said means having the feeding action along said throat to impart said feeding action, a crank on said 45 shaft, means operatively connected to said crank and to said lengthwise feeder, whereby said crank imparts said feeding action along said path, auxiliary means near said path, to operate upon material fed along 50 said path, and an operative connection from said crank to said auxiliary means comprising a slotted bar and a pin in said slot, whereby said auxiliary means is completely actuated during a part of the actuation of 55 said path, and an operative connection from said crank to said auxiliary means comprising a slotted bar and a pin in said slot, whereby said auxiliary means is completely actuated during a part of the actuation of 60 said lengthwise feeder.

57. In a machine of the character described, a structure having a throat, a guideway on said structure at a substantial angle to said throat, tractive means guided in said 65 guideway across said throat, a shaft, a lever

connected to said tractive means, a crank on said shaft, a member connected to said crank and having a connection to said lever adjustable along said lever, a feed-bar in said throat, a lever connected to said feed-bar, an eccentric on said shaft, a member connected to said eccentric and having a connection to the just mentioned lever adjustable along this lever, a cam on said shaft, a presser-head engaging with said 70 cam, a wedge between said presser-head and said feed-bar, a cushion element between said presser-head and said wedge, means yieldably connecting said presser-head to said feed-bar, a second feed-bar 75 yieldably pressed across said throat but prevented from material movement along said throat, a spring actuating said tractive means into a position in which it is tractively related to material operated upon by 80 the machine, means mounted near said guideway, temporarily actuating said tractive means out of said position, means to vary the relative time of action of this means, means for varying the degree of extension of said tractive means into said position, auxiliary means for operating upon said material near said guideway and throat, an operative connection from said 85 tractive means to said auxiliary means comprising a slotted bar and a pin in the slot, another auxiliary means for operating upon said material near said guideway and throat, an operative connection from said crank to this auxiliary means comprising a 90 slotted bar and a pin in the slot, one of said auxiliary means yieldably engaging said tractive means, a magazine to supply said material to said tractive means, near said guideway and the throat, a follower in said 95 magazine, acting at a substantial angle to said guideway, means over said magazine opposed to the action of said follower, and means whereby said magazine is movable 100 away from this opposing means. 105

58. In a machine of the character described, cross-feeding means having an action successively disposing preceding link elements at a substantial angle to respective next succeeding link elements, and tractive means comprising a gripper penetrating said preceding elements and gripping said succeeding elements for passing said succeeding elements through said preceding 115 elements. 120

59. In a machine of the character described, cross-feeding means having an action successively disposing preceding link elements at a substantial angle to respective next succeeding link elements, a gripper 125 comprising a tractively engaging projection and a jaw and having an action for approaching said projection and penetrating said preceding elements, said jaw then receding and permitting said projection to 130

tractively engage with said succeeding elements, and then approaching and gripping said succeeding elements for passing said succeeding elements through said preceding 5 elements, and mechanism coordinating said actions of said cross-feeding means and said gripper.

60. In a machine of the character described, cross-feeding means having an action 10 successively disposing preceding link elements at a substantial angle to respective next succeeding link elements, a gripper comprising a tractively engaging projection and a jaw and having an action for approaching said projection and penetrating said preceding elements, said jaw then receding and permitting said projection to tractively engage with said succeeding elements, and then approaching and gripping 15 said succeeding elements for passing said succeeding elements through said preceding elements, means for actuating said gripper, 70 a feed-block, a finger extensible out of and retractable into said block at one side thereof, means for completely reciprocating said feed-block toward and away from said gripper during a part of the action of said gripper, 75 means for extending and retracting said finger for each reciprocation, a magazine, and a follower in said magazine pressing elements therein against said side of said feed-block.

61. In a machine of the character described, cross-feeding means having an action 10 successively disposing preceding link elements at a substantial angle to respective next succeeding link elements, a gripper comprising a tractively engaging projection and a jaw and having an action for approaching said projection and penetrating 15 said preceding elements, said jaw then receding and permitting said projection to tractively engage with said succeeding elements, and then approaching and gripping 20 said succeeding elements through said preceding elements, means for actuating said gripper, a feed-block, a finger extensible out of and retractable into said block at one 25 surface thereof, means for reciprocating said feed-block toward and away from said gripper, means for extending and retracting said finger for each reciprocation, a magazine, and a follower in said magazine 30 pressing elements therein against said side of said feed-block.

62. In a machine of the character described, cross-feeding means having an action 10 successively disposing preceding link elements at a substantial angle to respective next succeeding link elements, a gripper comprising a tractively engaging projection and a jaw and having an action for approaching said projection and penetrating 15 said preceding elements, said jaw then receding and permitting said projection to tractively engage with said succeeding elements, and then approaching and gripping 20 said succeeding elements for passing said succeeding elements through said preceding elements, means for actuating said gripper, a feed-block, a finger extensible out of and retractable into said block at one surface thereof, means for reciprocating said feed-block toward and away from said gripper, 25 means for extending and retracting said finger for each reciprocation, an element yieldably mounted in said feed-block to be pressed into said block by said gripper when 30 the gripper and block approach each other and to extend therefrom as the gripper and block recede from each other, a magazine, and a follower in said magazine pressing elements therein against said side of said feed-block.

63. In a machine of the character described, cross-feeding means having an action 10 successively disposing preceding link elements at a substantial angle to respective next succeeding link elements, a gripper comprising a tractively engaging projection and a jaw and having an action for approaching said projection and penetrating said preceding elements, said jaw then receding and permitting said projection to tractively engage with said succeeding elements, and then approaching and gripping said succeeding elements for passing said succeeding elements through said preceding elements, means for actuating said gripper, 70 a feed-block, a finger extensible out of and retractable into said block at one side thereof, means for completely reciprocating said feed-block toward and away from said gripper during a part of the action of said gripper, 75 means for extending and retracting said finger for each reciprocation, a magazine, and a follower in said magazine pressing elements therein against said side of said feed-block.

64. In a machine of the character described, cross-feeding means having an action 10 successively disposing preceding link elements at a substantial angle to respective next succeeding link elements, a gripper comprising a tractively engaging projection and a jaw and having an action for approaching said projection and penetrating said preceding elements, said jaw then receding and permitting said projection to tractively engage with said succeeding elements, and then approaching and gripping 15 said succeeding elements through said preceding elements, means for actuating said gripper, 80 a feed-block, a finger extensible out of and retractable into said block at one side thereof, means for completely reciprocating said feed-block toward and away from said gripper during a part of the action of said gripper, 85 means for extending and retracting said finger for each reciprocation, a magazine, and a follower in said magazine pressing elements therein against said side of said feed-block.

65. In a machine of the character described, cross-feeding means having an action 10 successively disposing preceding link elements at a substantial angle to respective next succeeding link elements, a gripper comprising a tractively engaging projection and a jaw and having an action for approaching said projection and penetrating 15 said preceding elements, said jaw then receding and permitting said projection to tractively engage with said succeeding elements, and then approaching and gripping 20 said succeeding elements for passing said succeeding elements through said preceding elements, means for actuating said gripper, 90 a gripper-bar connected to said jaw, a stop for said bar, limiting said approach of said bar, a cam, a pusher-bar actuated by said cam and acting on said gripper-bar to cause 95 the recession of said jaw, and a spring to 100 cause approach of said jaw.

66. In a machine of the character described, cross-feeding means having an action 10 successively disposing preceding link elements at a substantial angle to respective next succeeding link elements, a gripper comprising a tractively engaging projection and a jaw and having an action for approaching said projection and penetrating 15 said preceding elements, said jaw then receding and permitting said projection to tractively engage with said succeeding elements, and then approaching and gripping 20 said succeeding elements for passing said succeeding elements through said preceding elements, means for actuating said gripper, 110 a gripper-bar connected to said jaw, a stop for said bar, limiting said approach of said bar, a cam, a pusher-bar actuated by said cam and acting on said gripper-bar to cause 115 the recession of said jaw, and a spring to 120 cause approach of said jaw.

67. In a machine of the character described, cross-feeding means having an action 10 successively disposing preceding link elements at a substantial angle to respective next succeeding link elements, a gripper comprising a tractively engaging projection and a jaw and having an action for approaching said projection and penetrating 15 said preceding elements, said jaw then receding and permitting said projection to tractively engage with said succeeding elements, and then approaching and gripping 20 said succeeding elements for passing said succeeding elements through said preceding elements, means for actuating said gripper, 125 a gripper-bar connected to said jaw, a stop for said bar, limiting said approach of said jaw, a cam, a pusher-bar actuated by said cam and acting on said gripper-bar to cause the recession of said jaw, a trip, engaging means on said gripper-bar engaging with said trip incident to the passing-through motion of said gripper to cause said jaw to again recede after said succeeding elements 130

have been passed through said preceding elements, and a spring to cause approach of said jaw.

65. In a machine of the character described, cross-feeding means having an action successively disposing preceding link elements at a substantial angle to respective next succeeding link elements, and a reciprocal tractive device comprising a carrier section and a tractive section removably secured to said carrier section, whereby different tractive sections can be mounted on said carrier section for penetrating said preceding elements of different sizes or designs and passing said succeeding elements of like sizes or designs through said preceding elements.

66. In a machine of the character described, cross-feeding means having an action successively disposing preceding link elements at a substantial angle to respective next succeeding link elements, a length-

wise feeder for passing said succeeding elements through said preceding elements, a turret element, and a plurality of magazines 25 mounted on said turret element to be successively positioned within reach of said lengthwise feeder, whereby each magazine thus positioned may supply said link elements to said lengthwise feeder and a magazine not thus positioned may be filled with the elements during said supply by the one magazine.

67. In a machine of the character described, feeding means comprising an element with a corrugated face to contact with soft flexible material to be fed, the corrugations of said face being defined by grooves or channels in said element running at a substantial angle to each other diagonally of the 40 direction of feeding of said feeding means to minimize moving of said material.

ANTHONY A. FETTE.

Certificate of Correction.

It is hereby certified that in Letters Patent No. 1,444,868, granted February 13, 1923, upon the application of Anthony A. Fette, of Cincinnati, Ohio, for an improvement in "Linking Machines," errors appear in the printed specification requiring correction as follows: Page 3, line 108, for the numeral "33" read ~~35~~; page 9, line 53, after the word "formed" strike out the semicolon and insert a comma; page 12, line 109, claim 30, for the word "meet" read *meeting*; page 17, line 42, claim 67, for the word "moving" read *marring*; and that the said Letters Patent should be read with these corrections therein that the same may conform to the record of the case in the Patent Office.

Signed and sealed this 5th day of June, A. D., 1923.

[SEAL.]

KARL FENNING,
Acting Commissioner of Patents.
